CLAIM

The ornamental design for a plug assembly, as shown and described.

DESCRIPTION

FIG. 1 is a first perspective view of a plug assembly; FIG. 2 is a second perspective view of the plug assembly of FIG. 1;

FIG. 3 is a front view of the plug assembly of FIG. 1;

FIG. 4 is a rear view of the plug assembly of FIG. 1;

FIG. 5 is a first side view of the plug assembly of FIG. 1;

FIG. 6 is a second side view of the plug assembly of FIG. 1;

FIG. 7 is a top view of the plug assembly of FIG. 1; and,

FIG. 8 is a bottom view of the plug assembly of FIG. 1.

In the drawings, the broken lines show portions of the plug assembly that form no part of the claimed design.
